UNITED STATES PATENT OFFICE

JOSEPH ERKES, OF PHILADELPHIA, PENNSYLVANIA

DESIGN FOR A PILE FABRIC

Application filed December 13, 1932. Serial No. 46,451. Term of patent 7 years.

To all whom it may concern:

Be it known that I, JOSEPH ERKES, a citizen of the United States, residing at 1104 Kenwyn Street, Frankford, Philadelphia, in the county of Philadelphia and Commonwealth of Pennsylvania, have invented a new, original, and ornamental Design for Pile Fabric, of which the following is a specifica-

tion, reference being had to the accompanying drawing, showing a part thereof.

The figure shows a face view of the pile fabric showing my new design.

I claim:

The ornamental design for a pile fabric, as shown.

JOSEPH ERKES.

CERTIFICATE OF CORRECTION.

Design No. 89,863.
